SHOWER HEAD

John O. Hruby, Jr., Burbank, Calif., assignor to John Drew, Gerald W. Frasier, and John O. Hruby, Jr., copartners

Application January 12, 1959, Serial No. 54,130

Term of patent 14 years

(Cl. D91—3)

Fig. 1.

Fig. 2.

Fig. 3.

Fig. 4.

Fig. 1 is a side elevation of a shower head, showing my new design;

Fig. 2 is a top plan view of the same;

Fig. 3 is an end elevation taken from the left of Fig. 1; and

Fig. 4 is a view of the water discharge end of the shower head.

I claim:

The ornamental design for a shower head, as shown.
